UNITED STATES PATENT OFFICE.

WALTER W. BUSSE, OF LOS ANGELES, CALIFORNIA.

COMB-CLEANER.

1,297,789.

Specification of Letters Patent. Patented Mar. 18, 1919.

Application filed December 26, 1917. Serial No. 208,925.

To all whom it may concern:

Be it known that I, WALTER W. BUSSE, a citizen of the United States, and resident of Los Angeles, in the county of Los Angeles and State of California, have invented certain new and useful Improvements in Comb-Cleaners, of which the following is a specification.

This invention relates to improvements 10 in toilet accessories and it is the principal object of the invention to provide a novel comb cleaner whereby foreign matter accumulated between the teeth of a comb can be quickly and thoroughly removed therefrom without doing injury to the comb.

Another and equally important object of the invention is to provide means for retaining the comb cleaning elements of the device in spaced relation in order that the same 20 can be readily engaged therebetween for cleaning:

Among other aims and objects of the invention may be recited, the provision of a device of the character mentioned with a view 25 to compactness, and in which the number of parts are few, the construction simple, the cost of production small, and efficiency and operation high.

The improvements in the details and arrangement of parts will be apparent from 30 an inspection of the accompanying drawings, in connection with the specific description hereinafter contained, and wherein the preferred embodiment of the invention is disclosed for the purpose of imparting a full understanding of the same.

In the drawings, I have shown a plan view of the improved device.

Having more particular reference to the 40 drawings and in connection with which like reference characters will designate corresponding parts throughout the several views, 1 and 2 represent the improved comb cleaning element retaining means, the retaining 45 means or holder 1 being formed from a single length of wire bent upon itself to provide a looped body, one side of which is slightly offset and provided with a plurality of curved fingers generally indicated by the 50 numeral 3, while the opposite side of the holder is looped upon itself as at 4 to pro-

vide for means whereby the same may be engaged with a hook or other suitable support.

The holder 2 is also formed from a single length of wire or other material bent upon 55 itself to form a looped body and having one side thereof offset and bent to provide a plurality of fingers generally indicated by the numeral 5.

The cleaning elements of my improved device consist of a single strand of wire, cord or other flexible means, one end of which is secured to the uppermost finger 5 of the holder 2 while the remaining portion is passed alternately about the fingers 3 and 60 the remaining fingers 5. By so arranging the strand, it will be understood that a plurality of comb cleaning elements generally indicated by the numeral 6 are provided, which elements may be engaged between the 65 teeth of a comb and the comb then moved thereover to cause the removal of all foreign matter accumulated therebetween. It is of course to be understood that the remaining end of the strand from which the cleaning 70 elements are composed is secured to the adjacent fingers 3 or 5 formed upon the holders 1 and 2 by knotting or otherwise engaging the same therewith.

When using the improved device, the 80 looped portion 4 of the holder 1 is engaged over a hook, nail or other suitable support while the holder 2 is engaged by the hand of the user. The comb to be cleaned is held in the other hand and engaged with the device in a manner to cause the arranging of 85 the various cleaning elements 6 between the teeth of the same. By moving the comb backwardly and forwardly over the cleaning elements, all foreign matter will be thoroughly removed therefrom without doing injury to the comb construction. Furthermore, by varying the position of the holder 2 with relation to the holder 1, that is by shifting the same laterally, the cleaning 90 elements 6 may be more closely positioned with relation to each other, thus rendering the same applicable for use in connection with fine tooth combs or the like. The cleaning elements may be readily removed and 95 others substituted therefor as it becomes necessary.

Manifestly, the construction shown is capable of considerable modification and such modification as is within the scope of my claim, I consider within the spirit of my invention.

I claim:—

A comb cleaner comprising looped end pieces having looped fingers formed in the adjacent sides thereof, the inner portions of

said looped fingers abutting whereby to close 10 the inner ends of said looped fingers, and a single strand arranged adjacent the end pieces and engaged with said looped fingers to provide a plurality of juxtaposed cleaning elements.

In testimony whereof I affix my signature hereto:

WALTER W. BUSSE.
